Attorney

UNITED STATES PATENT OFFICE.

BRUCE GREEN DE WOOLFSON, OF ALLENTOWN, PENNSYLVANIA.

GAME.

Application filed January 20, 1922. Serial No. 530,691.

To all whom it may concern:

Be it known that I, BRUCE GREEN DE WOOLFSON, a citizen of the United States of America, residing at Allentown, in the county of Lehigh and State of Pennsylvania, have invented certain new and useful Improvements in Games; and I do hereby declare that the following is a full, clear, concise, and exact description of the same, such 10 as will enable others skilled in the art to which it appertains to make and use the same.

This invention relates to improvements in games of chance having for an object to provide an amusing and interesting game which may be played by a number of persons, involving the calling of various letters or numerals presented upon suitable master cards, tags, or other game features by a 20 person other than a player of the game, such matter upon the master elements corresponding with matter, such as letters or numerals presented upon tags or the like removably secured to game cards called by the various 25 players; whereby, should any one of the cards of such players bear or be provided with the particular letter or numeral called from the master element, the same can be moved or indicated upon said card until the 30 full complement of its letters or numbers has been called or exhausted, whereupon the particular player holding that card is declared the winner of the game.

Other objects will be in part obvious and 35 in part pointed out hereinafter.

In order that the invention and its mode of application may be readily understood by persons skilled in the art, I have in the accompanying illustrative drawings and in 40 the detailed following description based thereon, set out one possible embodiment of the same.

In these drawings.

Figure 1 is a fragmentary plan view of 45 the game board;

Figure 2 comprehends elevations of certain of the master elements;

Figure 3 is a detail in perspective of the game board; and,

Figure 4 is a vertical transverse section therethrough.

Having more particular reference to the drawings, in connection with which like characters of reference will designate corresponding parts throughout, the improved

game may be stated to comprehend a plurality of master elements, such as tags, checks, or similar devices, shown upon the drawings and indicated by the numeral 1, these pieces being formed of card board, metal or other material and having presented upon one face thereof, letters, numerals, or symbols. In this particular embodiment, I have selected for the purpose of illustration, the arrangement of letters upon the faces of the master elements or checks 1, providing fifty two of such elements and individually arranging thereupon the various letters of the alphabet, both small and capital, such for example, as shown in the Figure 2, whereupon capital *R* is arranged upon one of the pieces, the small letter *o* upon another, the small letter *s* upon another, the small letter *i* upon another and the small letter *e* upon still another, thus constituting the proper name *Rosie*. In other words, the master elements include each letter of the alphabet both small and capital and in consequence, there would be one master element presenting the capital letter *R* and another presenting the small letter *r*, et cetera.

The various master elements are arranged in a bag, box, or other suitable receptacle and are individually selected by a person other than a player of the game and called by him to such players, whereupon the called master element is arranged upon a board or table 2 having a plurality of pins 3 arranged thereupon corresponding in number to the number of master elements, so that such elements, as called may be engaged with the various pins 3, openings 4 being formed in the upper or other suitable portions of said elements 1 as clearly shown whereby to facilitate such engagement.

The players of the game are provided with one or more cards 5, formed of paste board, metal or other suitable material having a series of spaced rings 6 engaged with the upper portion of the same throughout their lengths as shown in the Figure 3. Movable or slidably engaged with each of these rings 6 are checks or tags 7 having letters 8 presented upon the opposite sides of the same corresponding to the letters arranged upon the faces of the various master elements 1, such for example, as the capital letter *R*, the small letter *o* and so on, spelling the name *Rosie*, such as noted for purposes

of illustration in connection with the master elements 1.

During the progress of the game, should the person calling the letters upon the master elements 1, call the capital letter *R*, that particular player whose card is provided with a tag 7 lettered *R* would move or slide such letter about the particular ring 6 securing the same to the card 5 to the opposite side of such card, whereupon should the small letter *s* be called by the person holding the master elements 1, the tag bearing the small letter *s* upon the card 5 would be correspondingly moved to a position adjacent the first side of said card. If now the small letter *e* was called from the master element 1, those players whose cards were provided with tags bearing the letter *e* would move the same to the reverse or opposite sides of their respective cards as before. Thus, for example, should that particular player holding the card 5 bearing the five letters *R o s i e* have each of the lettered tags called by the person holding the master elements upon reversing the same, the proper name *Rosie* would be spelled and in consequence, since the tags upon this particular card would be exhausted that player would be declared winner of the game.

Of course, any number of cards may be given the various players, such as conditions or preference may dictate and in consequence, the length or duration of the game may be controlled accordingly.

Instead of providing the tags 7 with letters such as indicated at 8, it is to be expressly understood that I may employ numerals instead and therefore when all of the numeral bearing tags of a particular card of a player are called from the master elements and moved to the reversed side of said card the player holding the same would be declared winner of the game.

Because of the fact that the person calling the master elements 1 arranges the same individually upon the various pins 3 on the game board 2, it will also be understood that should question arise as to whether or not the letter or numeral of a particular tag had been called, the same could be readily verified from inspection of the master elements engaged with the pin 3 on the board 2.

Because of the fact that the various game cards 5 of the game have their particular game pieces or tags secured to the same, it will be appreciated that loss of such game

pieces with the resultant distorting of that particular card will be prevented.

Likewise, instead of employing a game board having a plurality of pins 3 arranged upon its surface, I may, if so desired, employ a tray having a plurality of pockets or compartments therein, into which the various master elements as they are called, may be placed.

Manifestly, the construction shown is capable of considerable modification and such modification as is within the scope of my claims I consider within the spirit of my invention.

I claim:

1. A game comprising in combination, a plurality of master elements having certain matter presented upon the faces thereof, game cards, a plurality of elements movably connected to said game cards having matter presented upon their opposite faces corresponding to the matter presented on said master elements and a game board having means thereon for individually retaining the master elements as they are called during playing of the game.

2. A game comprising in combination, a plurality of master elements having certain matter presented thereon, game cards, rings secured to the upper portions of said game cards, tags movably engaging said rings having matter presented upon the opposite faces thereof corresponding to the matter on said master elements and adapted to be moved from one side of said game card to the opposite side thereof upon display of corresponding matter on the master elements.

3. A game comprising in combination, a plurality of master elements having certain matter presented thereon, game cards, a plurality of spaced rings connected to said game cards and arranged equidistant throughout the same, tags movably engaging said rings having matter presented upon their opposite faces corresponding to the matter on said master elements and adapted to be moved from positions at one side of the card to positions at the opposite side of the same, and a game board having means thereon for individually receiving and retaining said master elements as they are called during playing of the game.

In witness whereof I have hereunto set my hand.

BRUCE GREEN DE WOOLESON.
